UNITED STATES PATENT OFFICE.

OTTO A. FREDERICKSON, OF WETHERSFIELD, CONNECTICUT, ASSIGNOR TO THE AMERICAN WIREMOLD COMPANY, OF HARTFORD, CONNECTICUT, A CORPORATION OF CONNECTICUT.

BRAIDING-MACHINE YARN CARRIER.

Application filed October 12, 1922. Serial No. 594,012.

To all whom it may concern:

Be it known that I, OTTO A. FREDERICKSON, a citizen of the United States, residing at Wethersfield, in the county of Hartford and State of Connecticut, have invented a new and useful Improvement in Braiding-Machine Yarn Carriers, of which the following is a specification.

This invention relates to the construction of the yarn carriers provided for use in rotary braiding machines of the type in which there are a plurality of radially arranged inner yarn carriers that are revolved rapidly in one direction and a plurality of annularly arranged outer yarn carriers that are revolved rapidly in the opposite direction, the yarn from the outer carriers being raised and lowered as the carriers are revolved so as to pass over and under the yarns from the inner carriers and form the braid at the center of the machine. A machine of this class is illustrated in Patent #1,331,672 to Anker Petersen, February 4, 1920.

In the prior machines of this character the inner ends of the inner yarn carriers have been supported by rolls that run on a track, either fixed or rotatable, and the outer ends of these carriers have been supported by rolls that are arranged on vertical arbors and run in a groove formed in the inner wall of the rotary drum that conveys the outer yarn carriers, which wall is provided at intervals with vertical slots for the passage of the yarns from the outer carriers. As the inner yarn carriers are revolved rapidly in one direction and the wall of the drum which carries the outer yarn carriers is revolved rapidly in the opposite direction, the resultant speed between the wall of the drum and the rolls on the outer ends of the inner carriers is high. Owing to the high speed and the outward pressure incident to the centrifugal action of the inner carriers these rolls and their arbors which cannot, on account of the environment, be efficiently lubricated, wear out very quickly and because of the lint gathered from the yarns the rolls soon stick and when they cease rotating they quickly wear flat. In order to reduce wear and noise it has been considered necessary to make the slots in the drum wall through which the outer yarns pass, and over which slots the rolls run, as narrow as possible, a factor which produces undue wear on the

yarns, increases the amount of lint gathered from the yarns and obstructs the free passage of knots made when the yarns break or the yarns run out and a new supply is attached.

The object of the present invention is to provide a construction for the inner yarn carriers of a machine of this character which will operate at a high speed more smoothly and with less noise and wear, than the prior constructions, and which will avoid hammering of the parts as the slots are passed by the inner carriers, and at the same time will permit the slots in the drum for the passage of the yarns from the outer carriers to be made wider thus reducing friction and wear on the yarns and permitting the free feed of such knots as are necessary to make in the outer yarns.

This end is attained in a very simple manner by removing the supporting rolls and their vertical arbors from the outer ends of the inner carriers and providing in place thereof shoes or flanges which will travel in the supporting groove in the wall of the drum and sustain the weight of the outer ends of the carriers, with comparatively little wear and no hammering as they pass the yarn slots. These shoes are sufficiently long to ensure stability to and freedom from vibration of the inner carriers as they are revolved, and the yarn slots in the drum wall may be as wide as desirable to permit the free passing of the outer yarns and all knots through them.

In the accompanying drawings Figure 1 shows a plan with portions broken away, of a few yarn carriers and the supporting and operating parts of a braiding machine of the type mentioned, the inner carriers being constructed according to this invention. Fig. 2 shows a vertical section of the parts of the machine shown in Fig. 1. Fig. 3 shows a detail of the outer end of one of the inner yarn carriers illustrating the relation of the shoe to the inner wall of the drum and a yarn slot therethrough. Fig. 4 shows in elevation the slotted wall of the drum and indicates the position of a yarn carrier back of the slot.

In the type of machine illustrated the inner bobbins, cops or tubes 6, which comprise braided or twisted cotton, linen or silk yarn wound upon cores 7, are placed in the inner

carriers 8. These carriers are frame-like and they are arranged radially in the machine. At the inner ends the inner carriers have rolls 9 which run upon a track on the 5 upper face of a disk 10, the hub of which is fastened to a tubular support 11 secured to the main frame 12 so as to stand upright at the center of the machine.

At their outer ends the carriers have rolls 10 13 which are engaged by pushing rolls 14 fixed to spindles 15 mounted in brackets 16 fastened to the upper face of a plate 17, the hub of which is secured to the upper end of a tubular shaft 18 that surrounds 15 the tubular support 11. Secured to the lower end of the shaft 18 is a gear 19. The driving pinion 20 meshes with this gear and rotates the parts in such manner that the pushing rolls 14 engage the carrier rolls 13 20 and cause the carriers to revolve about the axis of the machine. Anti-friction bearings 21 are arranged between the gear 19 and a race ring 22 attached to the frame for supporting these parts. The inner ends of the 25 pusher roll spindles 15 are provided with pinions 23 that mesh with teeth on the under face of the fixed disk 10. This causes the pushing rolls 14 to rotate as they are revolved and push the inner carriers 30 around.

The outer bobbins, cops or tubes 24 of braided or twisted cotton, linen or silk yarn wound upon paper cores 25 are placed in brackets 26 that are mounted on a ring 27 35 which is fastened to the upper edge of the drum 28. The hub 29 of this drum is free to turn on the tubular shaft 18 and the drum is supported by anti-friction bearings 30 arranged between its under face and the 40 top of an annular web 31 on the top of the gear 19. On the under face of the drum is a gear 32 that is engaged by the driving pinion 20 so that when the driving pinion is rotated and the inner carriers are 45 revolved in one direction the outer carriers will be revolved in the opposite direction.

The yarns 33 from the inner carriers are led through guides directly to the under 50 side of the braiding sleeve 34 at the center of the machine, while the yarns 35 from the outer carriers are led down through thread guides 36 and thence through slots 37 in the wall of the drum and to the braiding 55 sleeve. The thread guides 36 through which the outer yarns pass are at the ends of levers 38 which are pivoted to the outer wall of the drum and have rolls 39 that run in a cam groove 40 in a cam ring that 60 is attached to the top of the main frame. This means causes the yarns from the outer carriers to pass below and above the inner carriers as the carriers are revolved, an action well known in this type of machine.

65 For supporting the outer ends and sus-

taining the wear incident to the centrifugal thrust of the inner carriers, horizontal extensions are formed on, or shoes 41, are attached to the outer ends of these carriers. The outer edges of these shoes are curved 70 between their inwardly turned end portions on approximately the radius of the drum and they extend into a groove 42 formed in the inner wall of the drum. To place the inner carriers after they have been 75 loaded with yarn, the shoes are inserted into the groove 42 and the rolls 9 at the inner ends of the carriers are dropped upon the track with the rolls 13 in front of the pushing rolls 14. The inner carriers merely float, they are not permanently fastened to any part, as is necessary in order 80 that the yarns may pass above and below and so that they can be quickly removed and replaced as conditions require. When the machine is in operation the driving rolls 14 push against the carrier rolls 13 and cause the revolution of the carriers. As a result of the extended bearing surfaces of the shoes which support the outer 85 ends of the inner carriers the wear is slight and the carriers do not jump and vibrate while they are being revolved and the yarns are being unwound. There being no rolls to flat or arbors to wear in their bearings, 90 noise and shake are eliminated. Furthermore the shoes which sustain the outward or centrifugal thrust of the carriers are so long that there is no bumping or hammering as they pass the slots 37 through which 95 the yarns from the outer carriers pass, and therefore these slots may be made as wide as necessary to relieve the yarns from rubbing, and also to permit knots made when the ends of yarns are reached and others 100 attached, or when the two ends of a broken yarn are fastened together, to pass freely through the slots. The improvement described enables these machines to be run faster with less wear, noise and vibration 105 of the carriers than the prior constructions, with a consequent greater and better production.

The invention claimed is:—

1. In a braiding machine of the type provided with a drum having an annular groove formed in its inner surface to open inwardly and having vertical slots formed in its walls in intersecting relation with said groove to provide passages for the outer yarns, and constructed to support inner yarn carriers adjacent their inner and outer ends respectively to operate in a horizontal plane; inner yarn carriers for supporting yarn masses with their axes extending in a horizontal direction radially of the drum, and a shoe secured to the outer end of each of said carriers and formed as a flat plate extending from its carrier into said groove in a horizontal plane containing the longitudinal axis 115 120 125 130 135

of the yarn mass and constructed to span the vertical slots and slide smoothly over them as the carriers are advanced in their circular path.

- 5 2. In a braiding machine of the type provided with a drum having an annular groove formed in its inner surface to open inwardly and having vertical slots formed in its walls in intersecting relation with said groove to 10 provide passages for the outer yarns, and constructed to support inner yarn carriers adjacent their inner and outer ends respectively to operate in a horizontal plane; inner 15 yarn carriers for supporting yarn masses with their axes extending in a horizontal direction radially of the drum, and a shoe projecting from the outer end of each of said carriers and formed as a flat plate extending from its carriers in a horizontal plane containing the longitudinal axis of the yarn mass to enter the groove by movement radially of the drum and constructed to span the vertical slots and slide smoothly over them as the carriers are forced outwardly by centrifugal force while traveling in their circular path.

3. In a high-speed braiding machine, the combination of a revolving drum having an annular groove formed in its inner face to 30 open inwardly and the depressed wall of the groove formed as a thrust bearing surface, said drum having vertical slots formed through its walls so that they intersect the annular groove and provide passages of sufficient width to permit yarn to run freely therethrough and be reciprocated therein without fraying, inner yarn carriers arranged in a horizontal plane and supporting yarn masses with their axes extending radially of the drum, a race-way for supporting the inner end of said carriers, a shoe on each of the carriers formed as a flat plate extending from the carriers into the groove in a horizontal plane containing the longitudinal axis of the yarn mass and having a curved face constructed to slide against said thrust bearing surface and span the vertical slots to slide smoothly over them under the outward pressure of centrifugal force, and 40 means for advancing the carriers around their circular path.

4. In a high-speed braiding machine, the combination of a revolving drum having an annular groove formed in its inner face to 55 open inwardly and having vertical slots formed through its walls in intersecting relation with the groove to provide passages of sufficient width to permit yarn to run freely therethrough without fraying, inner yarn carriers arranged in a horizontal plane and supporting yarn masses with their axes ex-

tending radially of the drum, a race-way for supporting the inner end of said carriers, a shoe on each of the carriers adapted to be moved freely into said groove radially of the drum and formed as a flat plate extending from the carriers into the groove in a horizontal plane containing the longitudinal axis of the yarn mass and constructed to span the vertical slots to slide smoothly over them under the outward pressure of centrifugal force, and means for traveling the carriers in said horizontal plane. 65

5. In a braiding machine, the combination of a revolving drum supporting outer yarn supplies and having a vertical wall, the inner surface of which has formed therein an annular groove of less depth than the thickness of said wall, said drum having vertical slots formed through its walls so that they intersect the annular groove and provide passages of sufficient width to permit yarn to run freely therethrough and be reciprocated therein without fraying, inner yarn carriers arranged in a horizontal plane and supporting yarn masses with their axes extending radially of the drum, a race-way for supporting the inner end of said carriers, rollers upon the carriers engaging the race-way, a shoe on each of the carriers formed as a flat plate extending from the carriers into the groove in a horizontal plane containing the longitudinal axis of the yarn mass and constructed to span the vertical slots and slide smoothly over them under the outward pressure of centrifugal force, and rotating drivers for traveling the inner yarn carriers. 75 80 85 90 95

6. In a braiding machine, the combination of a revolving drum having an annular groove formed in its inner face to open inwardly and having relatively wide vertical slots formed through its walls in intersecting relation with the groove to provide passages of sufficient width to permit yarn to run freely therethrough without chafing, inner yarn carriers arranged in a horizontal plane and supporting yarn masses with their axes extending radially of the drum, a race-way for supporting the inner end of said carriers, a shoe on each carrier formed as a long flat plate rounded at its ends and extending from the carrier in the horizontal plane of the axis of the yarn mass and having a marginal side that enters said groove to provide a long curved bearing that conforms to and slides against the curved rear wall of the groove to span the vertical slots and slide smoothly over them under the outward pressure of centrifugal force, and means for advancing the carriers around their circular path. 100 105 110 115 120

OTTO A. FREDERICKSON.
